UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

ROTARY-SHAFT CHAIN-STITCH MACHINE.

Application filed July 20, 1922. Serial No. 576,270.

The invention relates to new and useful improvements in chain stitch sewing machines, and more particularly to a chain stitch sewing machine including an oscillating thread carrying looper.

An object of the invention is to provide a sewing machine of the above type wherein the parts of the stitching mechanism are all operated from a rotary shaft located 10 above the work support of the machine and preferably in the overhanging arm of the machine.

A further object of the invention is to provide a machine of the above type wherein 15 in the rotary movement of the upper rotating shaft is conveyed to a point below the plane of the work support where it may be connected directly to the looper operating mechanism.

20 A still further object of the invention is to provide a sewing machine of the above type wherein the thread carrying looper moves back and forth in a horizontal plane and is so actuated as to be given a dwell at 25 the forward end of its stroke.

A further object of the invention is to provide a sewing machine of the above type having a horizontally disposed threaded looper with means for connecting said 30 looper to its looper carrier so that the looper may be readily released and moved to a point where it may be accessible for threading.

These and other objects will in part be 35 obvious and will in part be hereinafter more fully disclosed.

In the drawings which show by way of illustration one embodiment of the invention—

40 Figure 1 is a view partly in side elevation and partly in section showing a sewing machine embodying my improvements;

Fig. 2 is a bottom plan view of the machine;

45 Fig. 3 is an enlarged plan view of the looper and the looper carrier;

Fig. 4 is a side view of the same;

Fig. 5 is a perspective view of the looper;

Fig. 6 is a perspective view of the looper 50 carrier;

Fig. 7 is a sectional view on the line 7—7 of Fig. 4, and

Fig. 8 is a detail showing the rotating crank for operating the looper.

In carrying out the invention, I have provided a construction of sewing machine which includes a work support, a standard supported thereby, an overhanging arm projecting from said standard, and carrying a head at its forward end in which the needle bar supporting the needle reciprocates. Mounted in this overhanging arm and standard is a rotary shaft and this rotary shaft reciprocates the needle bar. Said rotary shaft also is provided with adjustable feed eccentrics for operating the feeding mechanism. Also located in the standard is a vertical shaft which is geared to the upper rotating shaft in the overhanging arm so that the rotary movements of the upper shaft are imparted to the vertical shaft. This vertical shaft extends downwardly to a point below the work support where it carries a crank, and this crank is utilized for imparting oscillating movements to the looper. The looper is of a thread carrying type and is mounted so as to oscillate in a horizontal plane and the looper operating mechanism is so constructed as to give a dwell to the looper at the forward end of its stroke. The looper is mounted in the looper carrier so that it may be readily swung to position for threading and also readily removed for replacement when desired.

Referring more in detail to the drawings, my improved sewing machine includes a work support 1 having a depending flange 2 for housing the parts beneath the work support. Mounted on said work support is a standard 3 which is secured thereto by suitable bolts or screws 4, 4. This vertical standard 3 carries an overhanging arm 5, at the forward end of which is a head 6 in which the needle bar 7 reciprocates. Said needle bar 7 carries a needle 8. Also mounted in this head is a presser bar 9 carrying a presser foot 10.

Mounted in suitable bearings in the standard and in the overhanging arm is a rotary shaft 11. This rotary shaft terminates in the head 6 and is connected by suitable means to the needle bar for reciprocating the same. Said shaft is driven by a belt wheel 12.

The material is fed across the work support by a feed dog 13. This feed dog is carried by the feed bar 14 pivoted to an

arm 15 carried by a rock shaft 16. A second rock shaft 17 is provided with an arm 18 which supports the feed bar and raises and lowers the same. The rock shaft 16 is oscillated by means of an eccentric strap 19, while the shaft 17 is oscillated by means of an eccentric strap 20. These eccentric straps 19 and 20 cooperate with eccentrics on the main shaft 11. The eccentric operating strap 19 is carried by an adjustable plate 21 which is secured to a plate 22 fixed to the shaft, and this affords a means for varying the throw of the eccentric and thus the length of the stitch. This feeding mechanism forms no part of the present invention, and other forms of feeding mechanisms may be used in place thereof.

The looper which cooperates with the needle 8 is indicated at 23 in the drawings. Said looper is formed with a thread eye 24 at its forward end, a thread groove 25 and an opening 26 at its heel through which the thread passes. The looper is provided with an integral shank 27 from which extends a pin 28 and a lug 29.

The specific means shown for oscillating the looper and giving a dwell thereto at the forward end of its stroke is more clearly shown and described in my prior Patent No. 30 1,123,578, granted January 5, 1915.

The looper is carried by the looper carrier 30. This looper carrier 30 is mounted in a bracket 31 secured by screws 32, 32 to the bearing lug 33 in which the shaft 17 is mounted. The bracket 31 is provided with spaced arms in which the looper carrier oscillates. Said looper carrier 30 is fixed to a shaft 34. The looper carrier extends above the upper arm 31 and is provided with a head portion 35 having a socket 36 adapted to receive the pin 28 of the looper. Said head portion also has an overhanging bracket 37 underneath which the shank of the looper 27 passes. A latch 38 is pivoted at 39 to the head portion 35 of the looper carrier. After the looper supporting shank pin 28 has been fully seated in the socket 36, then the shank portion is swung underneath the bracket 37 and the latch 38 raised behind lug 29 to hold the looper in a rigid position on its carrier. The looper thus held oscillates back and forth with the carrier. When, however, it is desired to thread the looper, then the latch 38 can be readily moved down to the position shown in Fig. 6, and the looper swung on the pin 28 to withdraw it from underneath the throat plate 40 so that it may be readily reached through the opening closed by the cover plate 41. If it is necessary to remove the looper when it is in this position for threading, it may be readily lifted out of the carrier so that the latch 38 performs two functions. It permits the looper to be moved to threading position, and it also permits

the looper to be entirely removed from the carrier.

The looper oscillates back and forth in a horizontal plane and movements are imparted to the looper by a swinging arm 42 and a link 43 which pivotally connects the free end of the arm 42 to an arm 44 on the looper carrier. These parts are so disposed that when the looper is at the forward end of its stroke, the arm and the link are substantially in alinement and therefore the looper comes to a relatively long dwell, while when the looper is at the rear end of its stroke, the parts are in the position shown in Fig. 2 and there is practically no dwell given to the looper, it reverses its movement almost instantly.

The arm 42 is mounted to swing about a pivot post 45 and is oscillated by means of a link 46. The link 46 is connected to a crank pin 47 carried by a crank arm 48 on the lower end of a vertical shaft 49. This vertical shaft 49 is provided with a bevel gear 50 at its upper end which meshes with a bevel gear 51 fixed to the main shaft. There is a split bearing 52 which extends about the gears 50 and 51, and this bearing is secured to the arm of the machine in any suitable way. I have shown the bearing as secured to the arm by means of a screw 53. The bearing serves as a support for the upper end of the shaft 49 and holds the gears 50 and 51 in mesh. There is another bearing 54 for the lower end of the shaft 49.

From the above it will be apparent that I have provided a chain stitch machine wherein the thread carrying looper is oscillated by means connected with an upper rotary shaft, that is, a rotary shaft rotated in the overhanging arm, which rotary shaft reciprocates the needle. This actuating means for the looper includes a vertical shaft which conveys the rotary movements of the upper shaft to a point beneath the work support and the rotary movements of this upper shaft is there made available for direct connection with the looper mechanism for operating the same.

It is obvious that minor changes in the details of construction may be made without departing from the spirit of the invention as set forth in the appended claims.

Having thus described the invention, what I claim as new and desire to secure by Letters Patent, is:

1. The combination of a work support, a throat plate carried thereby, said work support having an opening at one side of said throat plate, a thread carrying looper beneath the work support, a carrier for said looper for supporting the same whereby the looper moves in a single horizontal plane, said looper having a pin attached to its shank adapted to removably and rotatably engage a socket in the looper carrier where-

by said looper may be moved about the axis of the pin for positioning the looper at one side of the throat plate for threading and whereby said looper may be removed from the carrier when in threading position, and a swinging latch for holding the looper in normal working position on said carrier.

2. The combination of a work support, a throat plate carried thereby, an opening at one side of said throat plate, a thread carrying looper beneath the work support, a carrier for said thread carrying looper for supporting the same whereby said looper moves in a single horizontal plane, said looper having a pin attached to its shank adapted to engage a socket in said looper carrier whereby said looper may be moved about the pin as an axis for positioning the same at one side of the throat plate for threading, and means at the end of said looper carrier having an overhanging bracket underneath which the shank of the looper may move when in normal position for stitching, and a latch for holding the looper in said stitching position on the carrier, said looper being free of the carrier except for said pin and bracket connection whereby when the latch is released, said looper may be readily removed from the carrier for replacement.

3. The combination of a work support, a throat plate carried thereby, an opening at one side of said throat plate, a thread carrying looper beneath the work support, a carrier for said thread carrying looper for supporting the same whereby said looper moves in a single horizontal plane, said looper having a pin attached to its shank adapted to engage a socket in said looper carrier whereby said looper may be moved about the pin as an axis for positioning the same at one side of the throat plate for threading, and means at the end of said looper carrier having an overhanging bracket underneath which the shank of the looper may move when in normal position for stitching, and a latch for holding the looper in said stitching position on the carrier, said looper being free of the carrier except for said pin and bracket connection whereby when the latch is released, said looper may be readily removed from the carrier for replacement.
